REFILLABLE MEMORANDUM PAD

Warner R. Buxton, Longmeadow, Mass.; Mabel Allen Buxton, executrix of said Warner R. Buxton, deceased, assignor to Buxton, Incorporated, a corporation of Massachusetts

Application May 29, 1940, Serial No. 337,777

8 Claims. (Cl. 281—19)

This invention relates to memorandum pads of the refillable type and more particularly to a pad of this type in which the support for the filler is made entirely of flexible material such as leather.

One object is to provide a structure of this character adapted for use in pocket receptacles such as wallets, letter cases and the like, without substantial sacrifice of the desirable flexibility of the receptacle.

A further object is to provide means for securely holding the filler sheets by means of the relatively yielding and flexible materials of which the receptacles are made, usually leather, without recourse to metal or other stiff, unyielding parts.

Other and further objects residing in the details of the construction will be made apparent in the following specification and claims.

In the accompanying drawing:

Fig. 1 is a plan view of a wallet in open position and provided with a memorandum pad according to my invention;

Fig. 2 is a sectional view on a larger scale substantially on line 2—2 of Fig. 1;

Fig. 3 is a fragmentary plan view similar to that of Fig. 1 but with the filler block removed;

Fig. 4 is a plan view of the filler block removed from the holder and with parts broken away;

Fig. 5 is a fragmentary section on a larger scale substantially on line 5—5 of Fig. 1 and showing part of the sheets of the filler block torn off; and

Figs. 6, 7 and 8 are fragmentary plan views, parts in some of the figures being broken away, showing three modifications in the construction of the filler block.

As above indicated two problems, the solution of which are the principal objects of the present invention, lay in the fact that the construction as a whole must be flexible and the holder for the filler block formed entirely of flexible material, such as relatively thin leather.

Referring to Fig. 1, the invention is shown embodied in a pocket receptacle of the wallet type, comprising an outer wall member 10 having a central fold line at 11 so that the two halves may be folded one upon the other in the usual manner. An inner wall member 12 is stitched or otherwise secured, as at 13, along its top, bottom, and outer side edge to the corresponding edges of the outer wall at one side of the fold line 11, forming a pocket between the inner and outer wall opening at its side toward the fold line.

The wall members 10 and 12 are formed of leather or similar material. The inner wall member 12 forms the supporting member for the filler block, generally indicated at 15, and together therewith forms the complete memorandum pad combination.

The means for releasably holding the filler block to its supporting member 12 is provided by forming spaced cuts 16 in the supporting sheet of leather 12. The end portions of the 5 cuts are turned outwardly as at 17 and these end portions are relieved, forming openings 18. The portion of the supporting sheet between the outwardly turned ends of the cuts form lips 20 beneath which, and through the cuts, end portions of the filler block are inserted as later more 10 fully explained. The extent to which the ends are turned depends upon the amount of lip overlap desired.

As best shown in Figs. 1, 2 and 4, my preferred 15 form of filler block comprises a backing sheet 22 of stiff paper or thin cardboard to which a plurality of superposed sheets of writing paper 23 are secured. The upper margin of the sheets 23 and the underlying backing sheet 22 are cut 20 away to form a relatively-narrow, centrally-positioned end portion 24, and the sheets 23 are secured together and to backing sheet 22 by staples 25 or other suitable means, a fabric binding 26 being glued around the stapled end portion. The sheets 23 are perforated, as at 27, 25 across the base of end portion 24. At the opposite end the backing sheet 22 of the filler block is cut away to form an end portion 28, the bottom edge of which is flush with the bottom 30 edges of sheets 23.

The filler block is mounted in the holder by inserting its end portion 24 through upper cut 16 and beneath upper lip 20, and similarly inserting its end portion 28 through lower cut 16 and beneath lower lip 20, as shown in Figs. 1 and 2. The cuts are so positioned and dimensioned relative to the end portions of the filler block that the end edges of the end portions of the filler block extend somewhat beyond the 40 outer edges of the relief openings 18 and the shoulders 29 at the bases of the end portions 24 and 28 seat in the relief openings 18, with the line of perforations 27 lying beneath the overlying lip 20 substantially along the line of junction of the lip with the body of the supporting sheet 12. When the filler block is in position in the holder the outer arcuate edges of the relief openings 18 spiral upwardly and around the edge of the filler block as is best shown at 30 in Figs. 1 and 2. For best results the size of the relief openings is so related to the maximum thickness of the filler blocks supplied for the holder that the dimension *a* (Fig. 3) approximates the maximum thickness of the filler block. By providing the relief openings 18 at the ends of the cuts the lip 20 is caused to engage the upper surface of the underlying end portion of the filler block flatly and uniformly across its entire width without tendency for the leather to form an arch over the end portion. As a result, despite the 45 fact that the holding parts are entirely of flex-

ible leather, the filler block is securely held even though backing sheet 22 is very thin or even omitted, as described below. The tightness of the gripping action permits the end portions 24 and 28 to be made quite narrow, substantially less than the full width of the filler block, which further increases the general flexibility of the assembly.

In the wallet combination shown in the drawing, the end portions of the filler block which extend through cuts 16 are positioned between outer wall 10 and the wall 12 closely adjacent the line of stitching which secures the walls together. The outer wall thus holds the end portions of the filler block snugly against the inner wall adjacent lip 20. As leaves are used and torn off along the line of perforations 27, the overlying lip 20, due to its tendency to return to its unstrained position, follows the retreating surface of the filler as shown in Fig. 5, thus maintaining its hold on the filler block.

My holder structure has a wide range of application and numerous modifications may be made. For example, the lower end portion which engages within the lower cut may be formed to include the full thickness of the writing sheets as at 28' in Fig. 6, or may take the form of an extension of the backing sheet beyond the edge of the writing sheets as at 28'' in Fig. 7. Also the cuts may be widened to correspond to the full width of the filler block as shown in Fig. 8, and the sheets 23' forming the filler block may be unbound and without a backing sheet, the end portions 24' of the block of sheets being inserted through cuts 16' and beneath lips 20'. In this form the sheets are simply withdrawn as used, the lips 20' maintaining their pressure on the ends of the block as it thickness diminishes.

It will be understood that the refillable memorandum pad combination described is applicable to various flexible pocket receptacles other than that shown and may be employed apart from receptacle structures. One advantage with which the invention is applied to pocket receptacles is evident from the fact that the outer wall of such receptacle is made to serve as a means for holding the inserted ends of the filler block snugly against the filler supporting sheet, while at the same time forming with the latter sheet a pocket for the reception of letters, papers and the like.

What I claim is:

1. A memorandum pad of the refillable type which comprises, a filler supporting member in the form of a sheet of flexible leather material, said sheet being provided with spaced cuts, the end portions of each cut being turned outwardly to form a free lip, and a block of filler sheets, opposite end portions of the filler block extending through said cuts and beneath said lips, the ends of the cuts being relieved to cause the lips to engage flatly against the outer surface of the underlying portions of the filler block.

2. A memorandum pad of the refillable type which comprises a filler supporting member in the form of a sheet of flexible leather material, said sheet being provided with spaced cuts, and a block of filler sheets, opposite end portions of the filler block extending through said cuts, the ends of the cuts being relieved to a degree commensurate with the thickness of the filler block.

3. A memorandum pad of the refillable type which comprises a filler supporting member in the form of a sheet of flexible leather material, said sheet being provided with spaced cuts, a block of filler sheets, opposite end portions of the

filler block extending through said cuts, the ends of the cuts being relieved to a degree commensurate with the thickness of the filler block, and an outer flexible wall member secured to the back of said supporting sheet to enclose the end portions of the filler block extending through the cuts.

4. A memorandum pad of the refillable type which comprises a filler supporting member in the form of a sheet of flexible leather material, said sheet being provided with spaced cuts, and a block of filler sheets, opposite end portions of the filler block extending through said cuts, the ends of the cuts being turned outwardly to form a lip and relieved to a degree commensurate with the thickness of the filler block, the sheets of the filler block being bound together at one end portion and perforated along a line adjacent the bound end portion for separation therefrom, said line of perforation lying beneath the lip of the cut through which the bound end extends.

5. A memorandum pad of the refillable type which comprises a filler supporting member in the form of a sheet of flexible leather material, said sheet being provided with spaced cuts, and a block of filler sheets, the sheets of the filler block being bound together and to a flexible backing member at one end, the corner portions of the bound end being cut away to form a narrow portion at that end of the filler block which narrow portion extends through one of said cuts, the corners of the unbound end of the backing member being cut away to form a narrow portion at the opposite end of the filler block which narrow portion extends through the other of said cuts.

6. A memorandum pad of the refillable type which comprises a filler supporting member in the form of a sheet of flexible leather material, said sheet being provided with spaced cuts, and a block of filler sheets, the sheets of the filler block being bound together and to a flexible backing member at one end, the corner portions of the bound end being cut away to form a narrow portion at that end of the filler block, which narrow portion extends through one of said cuts, the corners of the unbound end of the backing member only being cut away to form a narrow portion at the opposite end of the filler block which narrow portion extends through the other of said cuts, the end edge of the last-named narrow end portion being flush with the adjacent end edges of the sheets of the filler block.

7. A supporting device for refillable memorandum pads which comprises, a sheet of flexible leather material, said sheet being provided with spaced cuts, the end portions of each cut being turned outwardly to form a free lip, the ends of the cuts being relieved to cause the lips to engage flatly against the surface of the end portion of a filler block inserted through said cuts.

8. A filler block which comprises a plurality of filler sheets and a thin flexible backing member, means binding the filler sheets and backing member together at one end, the corner portions of the bound end, including the filler sheets and backing member, being cut away to form a narrow portion for engagement in a holder, the corners of the unbound end of the backing member only being cut away to form a narrow portion for engagement in a holder, the end edge of the last-named narrow portion being flush with the end edges of the filler sheets.
